UNITED STATES PATENT OFFICE.

WILLIAM A. SHORT AND EUSEBE LALIME, OF MALONE, NEW YORK.

BALANCED VALVE.

SPECIFICATION forming part of Letters Patent No. 367,557, dated August 2, 1887.

Application filed April 29, 1886. Serial No. 200,574. (No model.)

To all whom it may concern:

Be it known that we, WILLIAM A. SHORT and EUSEBE LALIME, of Malone, in the county of Franklin and State of New York, have invented a new and Improved Balanced Valve for Steam-Engines, of which the following is a full, clear, and exact description.

The object of our invention is to provide a new and improved cylindrical balance-valve for steam-engines, which is simple in construction and is completely balanced when the engine is reversed.

The invention consists of a cage placed in the steam-chest and having a vertical motion, and of a cylindrical slide-valve operating in the cage.

The invention also consists of various parts and details and combinations of the same, as will be fully described hereinafter, and then 20 pointed out in the claims.

Reference is to be had to the accompanying drawings, forming a part of this specification, in which similar letters of reference indicate corresponding parts in all the figures.

25 Figure 1 is a longitudinal central section of our improvement. Fig. 2 is a vertical cross-section of the cage and slide-valve on the line αx , Fig. 1. Fig. 3 is a plan view of the valve-bolt. Fig. 4 is a plan view of the valve-rod, 30 and Figs. 5 and 6 are side elevations of the valve packing-rings.

The steam-chest A is provided with the usual valve-seat, B, and the steam-ports C, C', and C''. On the valve-seat is placed the cage 35 D, which has a slight vertical motion between the seat B and the steam-chest cover E, being guided between the lugs or projections F on the sides of the steam-chest A. The cage D is provided with a central opening, G, in which 40 slides the valve H, and is provided with the ports I, I', and I'', which fit over the corresponding ports C, C', and C'' in the valve-seat B. The cylindrical slide-valve H consists of the body H', to which are secured the heads H' by means of the bolt H³, which is connected 45 to the valve-body H' and is provided on one

end with a recessed offset, H⁴, into which fits the T end J' of the valve-rod J. Each end of the valve H is provided with three cut packing-rings, K, placed one above the other, as 50 shown in Fig. 1, and held in place by a pin, K', passing into the valve-body H'.

It will be seen that the pressure of the steam on the valve H is equalized on both ends, as the steam in the steam-chest A can pass between the upper side of the cage D and the steam-chest cover E. If the engine is reversed, the back-pressure of the steam from either of the ports C, C', or C'' will lift the cage D off of the seat B, and thereby relieve the cage D and its slide-valve H from pressure. The cage slides in this short upward movement between the lugs F, the interlocking ends H⁴ and J' of the valve-bolt and the valve-rod permitting such movement.

Having thus fully described our invention, we claim as new and desire to secure by Letters Patent—

1. The cylindrical slide-valve H, consisting of the body portion H', the heads H², the bolt H³, having the offset H⁴ for the reception of the valve-rod, and the packing-rings K, placed one above the other at each end of the valve, substantially as herein shown and described.

2. In a balance-valve for steam-engines, a 75 steam-chest having inlet and outlet ports and lugs or projections on its sides, and a valve-rod having a T-end, in combination with a cage having inlet and outlet ports and being adapted to slide vertically between the lugs 80 on the sides of the steam-chest, a cylindrical valve having three packing-rings placed one above the other at each end and operating in the cage, and the valve-bolt having a recessed 85 projection in which fits the T-end of the valve-rod, substantially as shown and described.

WILLIAM A. SHORT.
EUSEBE LALIME.
